US0D1042065S

(12) **United States Design Patent** (10) **Patent No.:** **US D1,042,065 S**
(45) **Date of Patent:** **** Sep. 17, 2024**

(54) **PLIERS**

(71) Applicant: **Orbis Will GmbH + Co. KG**, Ahaus (DE)

(72) Inventor: **Markus Jepping**, Ahaus-Alstaette (DE)

(73) Assignee: **Orbis Will GmbH + Co. KG**, Ahaus (DE)

(**) Term: **15 Years**

(21) Appl. No.: **29/855,786**

(22) Filed: **Oct. 7, 2022**

(30) **Foreign Application Priority Data**

Apr. 8, 2022 (EM) 008932040-0009
Apr. 8, 2022 (EM) 008932040-0011
Apr. 8, 2022 (EM) 008932040-0012

(51) **LOC (14) Cl.** **08-05**

(52) **U.S. Cl.**

USPC **D8/52**

(57) **CLAIM**

The ornamental design for pliers, as shown and described.

DESCRIPTION

FIG. 1 is a front and left side perspective view of pliers, showing my new design;

FIG. 2 is a front view thereof;

FIG. 3 is a left side view thereof;

FIG. 4 is a rear view thereof;

FIG. 5 is a right side view thereof;

FIG. 6 is a top view thereof;

FIG. 7 is a bottom view thereof;

FIG. 8 is a cross-sectional view along lines 8-8 of FIG. 6;

FIG. 9 is a front and left side perspective view of pliers, showing another embodiment of my new design;

FIG. 10 is a front view thereof;

FIG. 11 is a left side view thereof;

FIG. 12 is a rear view thereof;

FIG. 13 is a right side view thereof;

FIG. 14 is a top view thereof;

FIG. 15 is a bottom view thereof; and,

FIG. 16 is a cross-sectional view along lines 16-16 of FIG. 14.

The features shown in broken lines depict portions of the pliers that form no part of the claimed design.

1 Claim, 14 Drawing Sheets
